WIDE BELT SANDING MACHINE

Gordon L. Schuster, Minneapolis, and Cecil D. Brother-
ton, Coon Rapids, Minn., assignors to Timesavers, Inc.

Filed Nov. 16, 1972, Ser. No. 307,047

Term of patent 14 years

Int. Cl. D15—09

U.S. Cl. D37—1 A

FIG. 1.

FIG. 2.

FIG. 1 is a perspective view of the wide belt sanding machine, viewing the same from its left front corner; and

FIG. 2 is a perspective view of the machine as seen from its diagonally opposite corner.

The top of the machine is plain.

We claim:

The ornamental design for a wide belt sanding machine, as shown and described.
